MEANS FOR APPLYING ADHESIVES

Paul Rentsch, Woodside, Long Island, N. Y., assignor to I. Miller & Sons, Inc., Long Island City, N. Y., a corporation of New York

Application April 12, 1937, Serial No. 136,355

2 Claims.

(Cl. 91—43)

This invention relates to means for applying adhesives to lengths of material, for example, bindings, tapes, etc. or other strips or sheets of indefinite lengths.

While the adhesive-applying means of the present invention is useful for other purposes, it is especially designed for coating the surfaces of strip material with adhesive preliminary to the association with said material of an inner strip in the manufacture of tapes, bindings, etc. of the type in which the outer strip, which is usually composed of leather, has longitudinally extending marginal edge portions folded over and covering the inner strip, which is usually composed of fabric. In the manufacture of such bindings, especially when rubber cement is used as the adhesive, difficulty is experienced in applying the adhesive to the inner surface of the strip material without soiling the outer surface of such material with the adhesive. One object of the present invention, therefore, is to provide means for obviating this difficulty, and for that purpose to facilitate the application of adhesive to one surface of the strip, or to a predetermined portion of said surface without coming in contact with the outer surface of said strip.

As the strip materials vary in width depending, among other things, upon the width of the bindings to be produced it is desirable to provide means for regulating the flow of cement to the strip material in accordance with the width thereof. Furthermore, in some cases, it is necessary to confine the application of the cement to a portion only of the width of the strip as for example to a marginal edge portion only of the strip, leaving the remaining portion of the width of the strip uncoated. This can be readily accomplished by the regulating means hereinbefore referred to.

A further object of the invention is to provide means for applying cement to and evenly distributing the same over the surface of the material.

Another object of the invention is generally to provide an adhesive-applying means which is simple in construction and designed to facilitate the application of cement to strip material so that large quantities of such material may be coated with cement in an efficient manner whereby the time and labor required for that purpose may be substantially reduced.

The above objects of the invention and other objects which might hereinafter appear will be fully understood from the following description considered with reference to the accompanying drawings.

In the drawings:

Fig. 1 is a perspective view of the adhesive-applying means, in accordance with the preferred embodiment of the invention;

Fig. 2 is a side elevation view, on a larger scale, of the adhesive-applying means shown in Fig. 1;

Fig. 3 is a transverse sectional view on the line 3—3 of Fig. 2;

Fig. 4 is a transverse sectional view on the line 4—4 of Fig. 2;

Fig. 5 is a detail plan view.

Referring more particularly to the drawings, the adhesive-applying means comprises an adhesive applicator-container 10 connected to an adhesive supply container 12 by a pipe 14 provided with an adjustable valve 15 for regulating the flow of adhesive from said supply container 12 to said applicator-container 10. An indicator, comprising a stationary dial 16 and a pointer 17 15 movable with the valve stem, is provided to facilitate adjustment of the valve for the desired flow of adhesive to container 10.

As here shown, the applicator-container 10, which is preferably made of metal, has a bottom 20 18, side walls 20, a front wall 22, a rear wall 24, and a top wall 26. All of said walls are assembled and secured together in a manner to define a cement chamber 28 to which the ingress of air is substantially eliminated so that the cement within said chamber may be maintained 25 in proper condition for application to the strip material.

Access of the cement to the material is provided through an opening in the form of a relatively narrow slot 30 formed in the top wall 26 30 and extending longitudinally thereof, the end of the slot being indicated at 30a and 30b in Fig. 2. The length of said slot is determined by the maximum width of the material which the present adhesive-applying means is designed to treat. The effective length of said slot, however, may be varied or adjusted in accordance with the present invention, and for that purpose, there is provided a valve block 32 slidably mounted on the upper surface of wall 26 over slot 30 and movable over said slot for regulating the length of the opening. Said block 32 is adjusted longitudinally by means of a screw 34 which has a screw-threaded engagement with said block 45 whereby rotation of said screw in either direction by manipulation of the screw head 36 is effective to move said valve block longitudinally of slot 30 for increasing and decreasing the length thereof. Said screw 34 constituting the valve 50 block adjusting means is mounted for rotation in the upwardly projecting portion 38 of wall 22, but is longitudinally immovable so that rotation of said screw as just described is effective to cause longitudinal movement of the valve block. Said wall portion 38 also constitutes means to limit the movement of valve block 32 in one direction, that is, the direction of maximum slot-opening illustrated in Fig. 1 which shows the 55

Fig. 1 is a perspective view of the adhesive-applying means, in accordance with the preferred embodiment of the invention;

forward end of block 32 close to or against said wall portion.

As here shown the supply container 12 is positioned above the applicator container 10 so that 5 the adhesive will flow by gravity from container 12 to container 10. If desired, however, said adhesive may be supplied to container 10 under fluid or other pressure instead of, or in addition to gravity pressure. When the apparatus is in 10 use, the chamber 28 is kept filled, there being a regulated flow of adhesive into said chamber under the control of valve 15 and out of said chamber in contact with the material to which it is applied. Thus, ordinarily, for the same 15 class of work, the valve 15 will be opened more or less as the opening through slot 30 is increased or decreased, respectively.

A frame 40 is mounted on top wall 26. Said frame is substantially U-shaped, having longitudinally extending side portions 42 and 44 and an end portion 46. Said side portions 42 and 44 are disposed at opposite sides of valve block 32 in engagement with the latter, constituting guideways therefor. Metal strips 48 are secured 20 to said side portions 42 and 44 by means of screws 50 in engagement with the upper surface of valve block 32, thus holding the latter in engagement with the top wall 26.

For applying cement to the strip material, the 30 latter is fed transversely of the applicator container 10 over the opening 30 therein. A guide passage for the strip material is provided by a groove 54 formed in the side portions 42 and 44 of frame 40. As the strip material is moved 35 across opening 30, it is pressed firmly against top wall 26 by resilient means here shown as a spring 56. Said spring is fastened at one end 58 thereof between the top surface of frame portion 44 and a releasable retaining member 60. Said spring retaining member 60 is pivoted at one 40 end 62 thereof to the frame portion 44 and is movable from the spring retaining position shown in Fig. 2 to the spring releasing position shown in Fig. 1. Said spring retaining member 45 may be held releasably in spring retaining position by a pivoted latch 64 fastened to the top of end portion 46 of frame 40.

As best shown in Fig. 3, the spring 56 is U-shaped and has an intermediate flat horizontally extending leg portion 66 which bears on the upper surface of the strip S, and a reflexed horizontally disposed and upwardly spaced or leg portion 68 which is engaged by the end of a screw 70, which is adjustable for regulating the 50 pressure of the spring on strip S. Said screw 70 is threaded through an opening in a bracket 72 and may be held in adjusted position by a holding nut 74 which releasably engages said bracket. Bracket 72 is mounted to the top wall 26 of applicator container 10 and is adjustable longitudinally of said wall. For that purpose the wall 60 engaging portion 76 of bracket 72 is provided with a slot 78 and is engaged in said slot by a holding screw 80 threaded into the top wall 26.

65 The manner of using the adhesive-applying means described above is more or less obvious from the above description. The valve block 32 is adjusted to provide an effective opening through the slot 30 of a length depending upon the width of strip material or upon the width of the portion of the strip to be coated with adhesive. The bracket 72 is also adjusted so that the spring 56 will be properly positioned with respect to the strip, and the pressure regulating screw 70 is adjusted to exert the proper degree 75

of pressure on the spring, depending upon the thickness of the strip material and the quantity of adhesive to be applied thereto. With the parts adjusted the strip material is then moved over the opening 30 and beneath the spring 56 5 which bears thereon. Thus, the adhesive is applied continuously and uniformly to the surface of the strip or to a portion of said surface, and the adhesive is prevented from contacting the outer surface of the strip or any surface portion 10 of the strip beyond the area of slot 30.

Thus, it is seen that the construction herein shown and described is well adapted to accomplish the several objects of the present invention. It will be understood, however, that the invention may be embodied otherwise than as here shown, and that certain changes in the construction and arrangement of parts of the present embodiment may likewise be made without departing from the present invention. 15 Therefore, I do not wish to be limited precisely to the present disclosure except as may be required by the appended claims considered with reference to the prior art.

What I claim and desire to secure by Letters 25 Patent is:

1. Adhesive-applying means comprising a container for the adhesive, said container having a wall provided with an elongated slot constituting an outlet opening for the passage of adhesive 30 from said container, a member movable on said wall over said slot longitudinally thereof for adjusting the length of the slot opening, and means for guiding a length of strip material for movement over said wall and transversely of the 35 length of said slot and over the open part thereof for coating the adjacent surface of said strip material with adhesive during the movement of said strip material across said slot, said slot-opening adjusting member having a surface part 40 extending transversely of said slot and constituting a part of said strip-guiding means, and spring means to press said strip against said wall at both longitudinally extending sides of said slot during the movement of said strip material 45 thereacross.

2. Adhesive-applying means comprising a container for the adhesive, said container having a wall provided with an elongated slot constituting an outlet opening for the passage of adhesive 50 from said container, a member movable on said wall over said slot longitudinally thereof for adjusting the length of the slot opening, and means for guiding a length of strip material for movement over said wall and transversely of the 55 length of said slot and over the open part thereof for coating the adjacent surface of said strip material with adhesive during the movement of said strip material across said slot, said slot-opening adjusting member having a surface part 60 extending transversely of said slot and constituting a part of said strip-guiding means, and spring means to press said strip against said wall at both longitudinally extending sides of said slot during the movement of said strip material 65 thereacross, said spring being U-shaped and having one leg disposed adjacent said wall for engagement with said material to resiliently press the latter against said wall, a pivoted member engageable with said leg of the spring for 70 releasably securing the latter in position on said wall, and a member engageable with the other leg of the spring for pressing the first mentioned leg thereof against the material.
